(57) **CLAIM**

The ornamental design for the combination creeper and seat, as shown and described.

DESCRIPTION

FIG. 1 is a perspective view of my new design in the seat position.

FIG. 2 is a left side view thereof.

FIG. 3 is a front view thereof.

FIG. 4 is a right side view thereof.

FIG. 5 is a bottom view thereof.

FIG. 6 is a top plan view thereof; and,

FIG. 7 is a perspective view of my new design when it is extended in the creeper position.

The broken line illustration of cushions shown in FIGS. 1, 2, 3, 4, 6 and 7 are for illustrative purposes only for forms no part of the claimed design.
